[57] **CLAIM**

The ornamental design for a frame for supporting electronic telecommunications equipment, as shown and described.

DESCRIPTION

FIG. 1 is a perspective view of a frame for supporting electronic telecommunications equipment, showing my new design;

FIG. 2 is a front elevational view thereof;

FIG. 3 is a back elevational view thereof;

FIG. 4 is a top plan view thereof;

FIG. 5 is a bottom plan view thereof;

FIG. 6 is a left side elevational view thereof; and

FIG. 7 is a right side elevational view thereof.

The frame for supporting electronic telecommunications equipment has been broken away in the center in FIGS. 2, 3, 4, and 5 for convenience of illustration.

FIG. 1
